UNITED STATES PATENT OFFICE.

ROY H. BURGESS, OF GLEN ELLYN, ILLINOIS, ASSIGNOR OF ONE-THIRD TO WILLIAM R. BURGESS, OF GLEN ELLYN, ILLINOIS.

VERTICAL-FILE-FOLDER MACHINE.

Application filed December 2, 1924. Serial No. 753,425.

To all whom it may concern:

Be it known that I, Roy H. BURGESS, a citizen of the United States, and a resident of the city of Glen Ellyn, county of Du Page, and State of Illinois, have invented certain new and useful Improvements in a Vertical-File-Folder Machine, of which the following is a specification.

My invention relates to a machine for producing vertical file folders, more particularly to a machine for manufacturing vertical file folders from an endless web of paper, and has for its main object the provision of a machine of this character which will be highly economical and efficient in use, effecting a great saving in labor and increasing production.

Another object of my invention is the provision of a machine of this character, in which provision is made for producing vertical file folders with either straight cut tops or die cut tops, and in which are combined the several separate operations comprising die cutting the tops in the web, scoring and folding the web, and finally cutting the folded web into folders.

Other objects will appear hereinafter.

The invention consists in the combinations and arrangements of parts hereinafter described and claimed.

The invention will be best understood by reference to the accompanying drawings forming a part of this specification, and in which,

Fig. 1 represents a side elevational view of my machine;

Fig. 2 represents a top plan view thereof;

Fig. 3 is a perspective view of a folder produced by my machine, the same having a die cut top;

Fig. 4 is a sectional view taken on line 4-4 of Fig. 5 and illustrating in particular the type of bearing employed for providing yieldable and adjustable mountings for the rollers;

Fig. 5 represents a front elevational view of the machine;

Fig. 6 shows a cross section through the creasing mechanism and folder cutting mechanism, this view being taken approximately on line 6-6 of Fig. 1;

Fig. 7 is a vertical sectional view taken on line 7-7 of Fig. 6;

Fig. 8 is a partial sectional view taken on line 8-8 of Fig. 1 and illustrating in

particular the mechanism for producing the die cut tops;

Fig. 9 shows a sectional view taken on line 9-9 of Fig. 5, this view illustrating the means employed for adjustably supporting the folder;

Fig. 10 is a section on line 10-10 of Fig. 9; and

Fig. 11 is a perspective view of a folder having a straight cut top.

The preferred form of construction, as illustrated in the accompanying drawings includes the supporting frames 12 and 13 which may consist of any suitable type or form of construction, the supporting frame 12 having supported thereon for unwinding action a roll 14 containing the continuous web of paper 15 from which the file folders are to be produced. Upon this frame 12 are rotatably supported the rolls 16, 17, 18 and 19 over which the web of paper is trained as best shown in Fig. 1, these rolls being revolved in an obvious manner by the pressure of the paper as it is moved or drawn along and serving as suitable instrumentalities for supporting and guiding the web of paper and also for cooperating with a pair of rollers 20 and 21 in maintaining the web properly tensioned, the said rollers 20 and 21 serving as means for pulling the paper along and unwinding the same from the roll 14.

The shafts 22 and 23 for the respective rollers 20 and 21 are mounted for rotation in the supporting frame 13 at the top thereof as best shown in Fig. 1. The shaft 22 for the roller 20 is yieldably and adjustably mounted in the frame. To this end, the ends of the shaft 22 are rotatably mounted in open slot-like bearings 24 (Fig. 4) and are operatively held by segmental bearings 25 which are acted on by the coiled springs 26 controlled by the adjusting screws 27 tapped through the end plates 28 which are secured to the frame by screws 29, the said end plates having thereon the spring guide members 30 which project into the open bearings 24. The adjusting screws 27 are provided with wing nuts 31 or other suitable means whereby to be adjusted for resiliently and operatively positioning the roller 20 with respect to the roller 21. In addition to pulling the web of paper along, the rollers 20 and 21, are formed to serve as scoring rollers and the same will be here-

2

inafter referred to as "scoring rollers". In order to carry out this function, the roller 20 is provided with annular ribs 32 which are adapted to annular recesses 33 provided in the other roller 21. The ribs 32 and recesses 33 are spaced apart a short distance in order to produce spaced scoring lines 34 on the web of paper. As will be readily understood by those familiar with the art 10 of producing vertical file folders one of these scoring lines serves as the line on which the folder is creased when folded, while the other scoring line serves as means of readily permitting the folder to expand laterally under the accumulation of papers filed therein when in use. The female roller 21 is driven through the meshing bevel gears 35, shaft 36 supported from the frame (Fig. 5), meshing bevel gears 37, shaft 38, meshing bevel gears 39 and shaft 40, which last mentioned shaft receives its power in a manner hereinafter to be described.

As best shown in Fig. 1, the web 15 just prior to being drawn between the scoring rollers is trained under a female die roller 41, an idle roller 42 operatively mounted adjacent the said female die roller 41 serving as means for training the web with relatively tight frictional engagement upon the 25 said female die roller 41, which as illustrated in Fig. 8, is provided with female die cutters 43 and 44. The axis 45 of the die cutting roller 41 is mounted in the frame for axial adjustment, the construction for this purpose being shown as consisting of a spring member 46 imprisoned between the closed end 47 of the bearing and adjacent end of the axis and an adjusting screw 47' tapped through the closed bearing end 48 to engage with the opposite end of the axis 45. Adapted to cooperate with the die cutter 43 is a male die cutter 49 on the wheel 50 adjustably mounted upon a shaft 51 which is yieldably and adjustably supported in the 30 frame by bearing mountings like those employed for the scoring roller 20. The male die cutter 49 cooperates with the female die cutter 43 to cut on the moving web the die cut tops or tabs 52 which appear on the completed file folders 53 (Fig. 3). The female die cutter 44 is of a different size from the die cutter 43 in order to produce a die cut top or tab 52 of a different length. In order to accomplish this purpose, the wheel carrying the male die cutter 49 may be removed from the shaft 51 and another male die cutter applied thereto that is suitable for cooperation with the female die cutter 44. By having the male die cutter as a detachable element, therefore, and by providing different sizes of female die cutters, provision is made for producing die cut tops or tabs 52 of different sizes.

The shaft 51 carries a bevel gear 54 in mesh with a bevel gear 55 on a shaft 56

which is coupled by means of an adjustable union 57 with a shaft 58, carrying a bevel gear 59 which is driven by a bevel gear 60 fixed on the main drive shaft 61. The adjustable union 57 includes cooperatively slotted and bolted disk members 62 designed to be readily separated in order to provide for the attachment and removal of the male die cutter on the shaft 51.

From the scoring rollers the web is drawn 75 downwardly over a folder 63 by means of a pair of creasing rollers 64 and 65 of which the roller 65 is mounted upon the shaft 40 hereinbefore mentioned. The creasing roller 64 is mounted for adjustment either towards or away from the creasing roller 65 by means of bearing mountings like those employed for the scoring roller 20 hereinbefore described. The shaft 40 carries a gear 66 which is driven through the intermediate 80 gears 67 and 68 (Fig. 5) from the gear wheel 69 fixed on the driving shaft 61.

The folder 63 comprises a body having a downwardly inclined ridge 70 from which the opposite sides 71 slope in such manner that the web while being drawn by and towards the creasing rollers will be folded over upon itself along one of the scoring lines preparatory to being creased in folded position by the creasing rollers. It is desirable that the folder 63 shall be mounted for adjustment in different directions in order that the ridge 70 thereof will be brought in proper relation to that scoring line on which the web is to be folded. To this end the folder is provided with fixed pins 72 having threaded portions 72' which extend through suitable openings provided in the plates 73 and 74 designed to engage upon opposite sides of the frame parts 75 having suitable enlarged openings 76 therein through which the pins 72 are passed, said pins and associated parts being secured tightly together by means of the securing nuts 77, as best illustrated in Fig. 9. As shown in Fig. 5 the folder 63 is preferably supported by means of three such adjustable constructions of which two are located near the top end thereof and one is located near the lower end or point of the same.

The web, having thus been drawn over the folder by means of which it is folded upon itself along a scoring line and having been creased by the creasing rollers, engages a feed board 78 with which is connected a stationary cutting knife 79 adjustably mounted upon an arm 80 of the supporting frame, the web in its course passing under a guide rod 81 and thence over the edge of the cutting knife 79 where it is severed into folders by means of a cooperating cutting knife 82 adjustably supported on a flange 83 carried by a roller 84 which is mounted upon the drive shaft 61. Each time the drive shaft 61 revolves, a completed folder is sev-

ered from the folded and creased web. The drive shaft 61 carries a driving pulley 85 to which may be applied a belt (not shown) operated from any suitable source 5 of power.

From the foregoing description taken in connection with the accompanying drawings the operation of my vertical file folder machine will be readily understood. The continuous web of paper 15 is drawn or pulled 10 by the scoring rollers 20 and 21, which impress upon the web the scoring lines 34, the web being drawn between the cooperating die cutters for the cutting thereon of the die cut tops or tabs 52. If the file folders are to have straight cut tops like the folder 15 illustrated in Fig. 11, the male die cutter 49 is removed from the shaft 51. From the scoring rollers the web is drawn by the 20 action of the creasing rollers over the folder 63 which is so adjusted that the scoring line on which the web is to be folded will coincide with the folder ridge 70. From the creasing rollers the folded and creased web then 25 passes to the feed board and stationary cutting knife where it is severed into separate folders by the rotary cutting knife.

While I have illustrated and described the preferred form of construction for carrying 30 my invention into effect, this is capable of variation and modification without departing from the spirit of the invention. I, therefore, do not wish to be limited to the precise details of construction set forth, but 35 desire to avail myself of such variations and modifications as come within the scope of the appended claims.

Having described my invention what I claim as new and desire to secure by Letters 40 Patent is:

1. A machine for producing vertical file folders comprising pulling rollers provided with scoring mechanism and means for feeding an endless web of paper thereto, mechanism 45 for folding the web comprising a folder and cooperating creasing rollers, a drive shaft carrying mechanism for cutting the web into folders, and means operated by the driving shaft for operating the pulling rollers, and cooperating creasing rollers simultaneously, substantially as described.

2. A machine for producing vertical file folders comprising means for supporting an endless web of paper, rollers for scoring the 55 web and pulling it along, a folder for folding the web, rollers for creasing and pulling along the web, means for adjusting said folder relatively to said scoring rollers and creasing rollers, a rotary knife for cutting the web into folders, and means for operating 60 a scoring roller, a creasing roller and said rotary knife simultaneously, substantially as described.

3. A machine for producing vertical file 65 folders comprising means for supporting an

endless web of paper, rollers for scoring the web and pulling it along, rotary die members for producing die cut tops in the web, a folder for folding the web, rollers for creasing and pulling along the web, a driving shaft carrying a rotary knife for cutting the folded web into folders, means operated by said shaft for driving a scoring roller, means operated by said shaft for driving the rotary die member, and means operated 70 by said shaft for driving a creasing roller, all simultaneously, substantially as described.

4. A machine for producing vertical file folders comprising means whereby to support and move along an endless web of 80 paper, a pair of rollers for scoring the web, a pair of rotary die cutters for producing die cut tops in the web, a folder, means for adjusting the folder for folding the web along a scoring line, a pair of rollers for creasing 85 the web on the folding line and a driving shaft carrying a knife for severing the folded web, substantially as described.

5. A machine for producing vertical file folders comprising means to move along an 90 endless web of paper, a pair of rollers for scoring the web, a folder, means for adjusting the folder for folding the web along a scoring line, a pair of rollers for creasing 95 the web on a folding line, a rotary knife for cutting folders from the folded web, and a drive shaft carrying said knife, substantially as described.

6. In a machine for producing vertical file folders, the combination with means for moving along an endless web of paper, of mechanism for producing die cut tops on said web comprising a die cutting roll contacting with said web and actuated thereby, a shaft, a knife mounted on the shaft and cooperating with said roll, said shaft being relatively adjustable with respect to said roll, and means for driving said shaft in synchronism to the travel of said web, substantially as described.

7. In a machine for producing vertical file folders, the combination with means for moving along an endless web of paper, of mechanism for producing die cut tops in said web as it moves along comprising a die cutting roll contacting with said web and actuated thereby, a shaft, a knife mounted on the shaft and cooperating with said roll, bearings supporting said roll for relative endwise movement and adjustment, bearings supporting said shaft for relative sidewise movement and adjustment, and means for driving said shaft, substantially as described.

8. In a machine for producing vertical file folders, the combination with means for moving along an endless web of paper, of mechanism for producing die cut tops on said web as it moves along comprising a 125 roller provided with female die cutters of 130

different sizes, a shaft supported in relation to said roller, a male die cutter removably mounted on said shaft, bearing supporting said roller for relative endwise movement 5 and adjustment, bearings supporting said shaft for relative sidewise movement and adjustment, and means for driving said shaft, substantially as described.

9. In a machine for producing vertical

10 file folders, the combination with means for moving along an endless web of paper, of mechanism for folding said web, mechanism for cutting the folded web into folders comprising a stationary cutting knife, a 15 drive shaft and a cutting knife supported on said drive shaft longitudinally thereof for cooperating with said stationary cutting knife, substantially as described.

10. In a machine for producing vertical

20 file folders, the combination with means for moving along an endless web of paper, of mechanism for folding said web, mechanism for cutting the folded web transversely into folders comprising a feed board combined 25 with a stationary cutting knife, a shaft, a cutting knife adjustably carried by said shaft and extending longitudinally thereof to cooperate with the stationary knife, and means for driving said shaft, substantially as de- 30 scribed.

11. In a machine for producing vertical file folders, the combination with means for supporting an endless web of paper for movement, of a pair of rollers for pulling

35 said web along and for making scoring lines on said web, a pair of creasing rollers for pulling said web along and creasing it, a

folder interposed between said pairs of rollers and over which said web is drawn to folding shape, means for adjusting said 40 folder comprising pins projecting therefrom, and supports in which said pins are independently adjustable both longitudinally and laterally, substantially as described.

12. In combination, an endless web roll 45 mounted for unwinding action; a pair of rollers for pulling said web along and unwinding it from said roll; means associated with said rollers for making scoring lines on said web; die cutting means for cutting 50 tabs on the side edge of the moving web before the scoring operation takes place; a folder adjustable to said scoring line; a pair of creasing rolls for drawing said web over the folder and creasing it as folded; and 55 means for cutting the folded and creased web transversely to provide folders of suitable length, substantially as described.

13. In combination, an endless web roll 60 mounted for unwinding action; rollers for pulling the web along; a roller disposed for axial adjustment engaging the movable web and rotated thereby; a die cutter on said roller; a shaft yieldably and adjustably arranged in relation to said roller; a member 65 adjustable on said shaft for cooperating with said die cutters in cutting tabs on said web as it travels; and means for rotating said shaft in relation to the rotation of said 70 pulling rollers, substantially as described.

In testimony whereof I have signed my name to this specification.

ROY H. BURGESS.
